(57) CLAIM

The ornamental design for a set of eyeliner stickers and shaping stencils, as shown and described.

DESCRIPTION

FIG. 1 is an exploded perspective view of a set of eyeliner stickers and shaping stencils showing my new design; and, FIG. 2 is a top view thereof.

The broken lines shown represent unclaimed subject matter and form no part of the claimed design. The shade lines shown represent surface shading and not surface ornamentation.

1 Claim, 2 Drawing Sheets

FIG. 1

FIG. 2
